UNITED STATES PATENT OFFICE.

JOHN M. JONES, OF PALMYRA, NEW YORK.

PRINTING-MACHINE.

Specification forming part of Letters Patent No. 14,919, dated May 20, 1856.

To all whom it may concern:

Be it known that I, JOHN M. JONES, of the town of Palmyra, in the county of Wayne, in the State of New York, have made certain Improvements in Domestic Printing-Machines; and I do hereby declare that the following is a full and exact description thereof, reference being had to the accompanying drawings, and to the letters of reference marked thereon.

Figure I represents a top view of the machine. Fig. II is a longitudinal section; and Fig. III is a view of the under side, showing the different mechanism.

A is a wheel with a notched or toothed rim, situated in a horizontal position, and has two motions, a revolving or rotary motion, and a motion in the direction of its axis. The type is attached around the outside of the periphery of the rim with the face of the type projecting a little below the same.

B is the index-ring, situated upon the wheel A and held stationary by the arm a.

D is a lever attached to the bracket E, one end of said bracket is fastened to the wheel A, and the other end passes through an opening in the wheel A and rests upon a circular plate, N, lying below the wheel A and attached to the frame F of the machine. By this lever D the wheel A receives through the hand of the operator its revolving or rotary motion, and all the mechanism of the machine is worked by said lever.

C is an arm, one end of which is attached to a pivot in the stand O and the other end fits into the notches or teeth on the rim of the wheel A. By this arm C the second motion is communicated to the wheel A, by which the type is pressed down and made to bear on the paper when an impression is to be made, and at the same time insuring always the right position of the wheel A.

G is a wheel attached to a hollow shaft, P, which passes through the center of the wheel A, and is attached to the same by the pin d in such a manner as to turn round with said wheel A, and having at the same time a second motion, forward or backward, communicated to the same. Around the outside periphery of the wheel G projections are made corresponding in number and thickness with the type round the wheel A.

H is an endless band to which the paper is

fastened and attached to the carriage L, which moves on the ways K K.

M is a rod to which the carriage L is attached. This rod M is connected with the rod Q, moving in the guides h h, and is acted upon by the projections on the periphery of the wheel G, as well as by the spring s, by which arrangement the carriage L, with the paper attached, is caused to move according to the thickness of the type, together with the space between the letters, as soon as the impression is made.

R is a lever connected with the rod Q and used to move the carriage L for the purpose of making the proper spaces between the words.

S is a rod passing through the hollow shaft P of the wheel G and connecting the end of the lever D with the arm 4, fast on the rock-shaft X, to move the different parts.

J J are the ink-rollers by which the type is inked.

The letter-paper is attached to the band H on the carriage L, which latter is then placed on the rod M and upon the ways K K and pushed in toward the center of the wheel before printing is commenced. As the wheel A, with the type attached, revolves or is moved round by the handle D, each type receives its ink for printing as the same passes over the ink-rollers J J. The operator turns by the handle D the wheel A until the pointer V is opposite the letter on the index-ring B which he intends to print, and then presses said handle downward. By this operation the arm C is pressed into the tooth on the rim of the wheel A above the type corresponding to the letter indicated on the index-ring B, and presses the wheel A down, so that this specific letter leaves its impression on the paper. This arm C receives its motion from the lever D through the rods n m, in connection with the arms 2, 3, and 6, fast on the rock-shafts X and Y. By the same operation the rod p, which is connected with the arm 5 on the rock-shaft Y and with the hub of the wheel G, communicates to said wheel a side motion, acting thereby upon the rod Q, thereby moving the carriage L a small distance forward corresponding to the thickness of the type, together with the space necessary from one letter to the other. The wheel G is pushed back again by the action of the spring w and the rod Q by the action of

the spring s. At the completion of every word the lever R, the end of which projects through the frame, is moved by the finger, which acts upon the rod Q and moves thereby the carriage L the required distance. When the carriage L has moved so far as to bring the line to the end of the paper, the carriage is run back by hand upon its ways K K, in doing which the endless band H, with the paper attached, is turned around sufficiently far to leave space between this and the next line, when the carriage is again pushed in toward the center of the wheel A.

What I claim as my invention, and desire to secure by Letters Patent, is—

1. The manner of attaching the lever D to the wheel A so that the same may turn said wheel while its fulcrum rests upon a fixed plate, N, situated below the revolving wheel A, allowing at the same time a revolving motion and a motion in the direction of its axis to the wheel A, said lever D being connected

with the mechanism by the rod S, passing through the hollow shaft of the wheel G, substantially as described.

2. The arrangement and use of the lever C for the purpose of pressing down the type on the paper when an impression is to be made, and at the same time insure always the right position of the type and wheel A, in the manner specified.

3. The swinging wheel G, attached to a hollow shaft, having projections on its periphery corresponding in number and thickness to the type, for the purpose of moving the carriage L, with the paper attached, the exact distance necessary for printing one letter after the other, acted on and arranged in the manner substantially as described.

JOHN M. JONES.
